UNITED STATES PATENT OFFICE.

CORNELL FLAGSTAD, OF MINNEAPOLIS, MINNESOTA, ASSIGNOR OF NINETY-FIVE ONE-HUNDREDTHS TO THE FOLDING CRATE AND BOX COMPANY, OF MINNEAPOLIS, MINNESOTA, A CORPORATION.

COLLAPSIBLE CARRIER.

Application filed January 5, 1925. Serial No. 589.

To all whom it may concern:

Be it known that I, CORNELL FLAGSTAD, a citizen of the United States, residing at Minneapolis, in the county of Hennepin and State of Minnesota, have invented 5 certain new and useful Improvements in Collapsible Carriers, of which the following is a specification.

This invention relates to collapsible carriers and the main object is to provide an improved type of shipping crate in which the side and end sections are hingedly secured together, and in which the cover, or top and bottom sections, are detachably secured in such a manner that they may be quickly and easily attached and detached to the said side and end sections when the crate is to be set up or collapsed. Some of the features disclosed and claimed in this 10 application are also shown in my pending application Ser. 677,175, which was filed on November 26, 1923, for collapsible crate, and in so far as such features are common to the two applications the present application 15 may be considered as a division of said former application.

In the accompanying drawings forming a part of this application:

Figure 1 is a top (or bottom) plan view 20 of a crate embodying my invention.

Figure 2 is an enlarged end view of the 25 crate as seen when collapsed, certain portions being broken out.

Figure 3 is an enlarged detail sectional 30 view of the line 3—3 in Figure 1, the central portion of the view being broken out.

Figure 4 is an enlarged detail section as 35 seen on the line 4—4 in Figure 3.

Figure 5 is a detail view of a hinge member 40 used in the crate.

Figure 6 is a sectional detail view of one corner of the crate, as seen when the 45 crate is collapsed.

Figure 7 is a (reduced) modification of 50 the corner structure shown in Figure 6.

Figure 8 is an enlarged detail section on the line 8—8 in Figure 1.

Figure 9 is an enlarged detail section on the line 9—9 in Figure 1.

Figure 10 is a perspective detail showing 55 a modification in the hinge structure.

Figure 11 is a perspective detail showing a further modified corner hinge.

Figure 12 is a plan view of a crate which embodies certain important modifications 55 over the crate shown in Figure 1.

Figures 13 and 14 are enlarged detail 60 sectional views on the lines 13—13 and 14—14, respectively in Figure 12.

Referring to the drawings more particularly and by reference characters, A and B designate the side sections of a crate which are hingedly connected, as at C and D, to the end sections E and F, in such a manner that when the crate is to be collapsed these 65 sections will swing through a parallelogram to the position shown in Figure 2. The crate is closed by a top or cover section G and a bottom section H. The cover and bottom sections of the crate may be constructed the same, so that Figures 1 and 12 70 may be considered as either top or bottom plan views, but as it is desirable in some instances to use a bottom section of a different type I have, in Figure 2, shown the 75 section H hinged to the side section B, as at 15, so that it can be folded up against that side section and be contained within the crate when the latter is collapsed or knocked down. When the crate is in a set up position the swinging end of the section H is 80 dropped down so as to rest on a strip 16 which is permanently secured upon the inner side of the opposite side section A, and at its lower edge

The various sections of the crate are made up of transversely crossed slats which are nailed or otherwise secured together in any suitable manner. Thus the side and end sections consist of horizontal and vertical slats 90 17—18, 19—20, 21—22, and 23—24, and the base section H (Figure 2) is made up of longitudinal slats 25 connected by transverse slats 26. The cover section G and the modification (G¹) thereof, shown in 95 Figures 12, 13, 14, will be described later.

The vertical sections A—E and B—G are, respectively, joined together by a hinge structure D such as is shown particularly in Figure 6. This hinge consists primarily 100 of a substantially U-shaped bail or pintle member 27, and a strap iron leaf 28 forming

- a pintle for the member 27. This pintle member 27 is secured between the slats 17 and 18^a (or 20^a) and is substantially the same as the pintle member shown in Figure 5, except that the end barbs 29 are imbedded at right angles into one of the slats, to prevent the member from being pulled out of place. The slats 18^a and 22^a are secured, preferably by nails, as shown, to the extremities of the 10 horizontal slats 17 and 21, so as to clamp the entire lengths of the hinged members, and in order that these sections may be swung to a right angular or set up position the inner edges of the slats 18^a and 22^a are beveled, 15 as indicated at 30 in Figures 1, 2, and 6. This construction thus effects a relatively close or tight corner joint at all times which, of course, is highly desirable in some types of crates.
- 20 In the modified corner construction D¹, illustrated in Figure 7, the vertical slats 18^b and 22^b are not beveled, as in Figure 6, but the outer edge of the slat 18^b is spaced from the pintle center the distance equal to the 25 thickness of the slat 22^b so that the two slats will close together when the sections A and E are at right angles to each other, as indicated by the dotted lines 31. In this case it may also be noted that the two leaves of 30 the bearing strap 32 are not secured together as with 28 in Figure 6, but straddle and are secured over the end of the slat 17, one end being secured between the two slats 18 and 18^b.
- 35 At the other ends (from D) of the side and end sections a corner construction is provided such as shown particularly in Figure 4. In this event the hinge bail 33 is secured between the slats 23 and 24^a, but the 40 pivoting center of the hinge is offset from the section A by a vertical strip or slat 34, and the slats 24 and 34 are beveled, as at 25, so that the crate may be collapsed (see Figure 2). Thus the members 34 will effect a 45 space between the sections A, E and B, F for the reception of the bottom section H when the crate is knocked down, and by varying the size of the members 34 it will be apparent that both the top and bottom sections 50 may be returned in the collapsed crate if so desired. In Figures 11 and 12 is illustrated a modification C¹ of the hinge C. In this event, instead of using an offsetting member such as 34, I employ a double hinge leaf 35 55 (similar to 28) and provide the pintle member 36 with an offset extension 37 to effect the desired spacing within the crate when it is folded up.
- 60 In Figure 10 I have shown a further modification of a crate hinge construction, and it consists primarily of two wire members 38 and 39, the ends of which are imbedded and secured in the adjacent crate sections, while the intermediate portions 40 and 41 are 65 looped and connected, as at 42, to form a pivoting connection. A hinge of this type may be used either at the corners, such as at D, or, if the shank portions 40-41 are long enough the spacing, such as by the slats 34, 70 will be effected.
- 70 The crate closures or head sections for closing the crates will now be described, as follows: The cover section G, shown in Figures 1, 3, 8 and 9, consists of two interslidingly secured frames, the one having longitudinal slats 43 and 44, connected by transverse slats 45, 46, 47 and 48; and the other or sliding frame consisting of longitudinal slats 49, 50 and 51, which slide on the slats 45-48, and transverse slats 52, 53, and 54, 75 which are secured to the slats 49-51, but operate under and project beyond the slats 43, 44. The stationary cover frame 43-48 fits snugly between the side sections A and B, and thus braces the crate in a rectangular 80 condition, and the ends of the slats 43, 44 project beyond the slats 45, 48 so as to rest and be supported on the top edges of the end sections E and F.
- 85 The slats 52, 53, and 54 project beyond 90 the stationary frame for engagement in apertures 55 and 56 in the upper rails 17 and 19 of the side sections, to lock the cover in place on the crate. This sliding movement of the frame is permitted by reason of the 95 slat 51 being spaced inwardly from the slat 44, thus allowing a limited movement of the slats 49 and 51 between the slats 43 and 44. As shown in Figures 1 and 3 the movable 100 cover bolts 52, 53, and 54 extend into both side sections and the cover is locked in place. To remove the cover it is necessary to slide the movable frame until the slat 51 meets the slat 44. This will free the cover from the side section A, as indicated by dotted 105 lines, so that it may be lifted and withdrawn from the side section B. To replace the cover this operation is reversed.
- 110 To secure the two cover frames in releasably locked positions with respect to each other, I have provided devices as shown in Figures 1, 8 and 9. The device shown in Figures 1 and 9 consists of a plate 57 which is secured on the slat 47 and has a tooth 58 which engages upwardly against the slat 50, 115 when the cover is closed, so that the cover frames cannot be returned to opening position without first manually depressing the slat 47 to free the tooth 58. In the latch shown in Figure 8 I have provided the slat 120 46 with a hole 59 through which projects a manually depressible dog 60 of a spring member 61. The dog 60 stops the retracting or releasing movement of the slat 50, unless depressed, and springs back into its 125 latching position as soon as the cover frames are again in closed positions with respect to the crate.

The cover shown in Figures 12, 13, and 14 is a one piece section, consisting of horizontal slats 62, 63, and 64 and transverse slats 65, 66, and 67, secured thereunder. This 5 cover section fits between the side sections and rests on the end sections, as in Figure 1. The cover is secured in place by means of a pair of sliding bolts 68 and 69. The bolt 68 operates in a channel in the slot 62, and 10 rides on a wearing plate 70 secured on the slat 66. Its sliding movement is limited by a pair of vertical end extensions 71 and 72, so that when the bolt is locked in place it 15 will not only hold the cover down, but will also prevent the side section from bulging or spreading away from the cover section. And, with the same objects and advantages in view I have also shown the cover 20 G in Figure 1, as provided with similar anti-bulging members. In Figure 12 and 14 I have shown a further modification of the device by providing a metallic bridging member 73 between two of the slats 20, for engagement by the locking member 69, which, 25 in this event, need not project through the side section.

To engage and disengage the bolts 68 or 69 it is of course necessary to depress the cover at that point, so as to allow the 30 tensions 72 to be moved into and out of locking positions.

It is understood that various modifications may be made in the general design and structural details of the invention as herein illustrated and described, providing however, that such modifications come within the spirit and scope of the appended claims.

Having now therefore, fully shown and described my invention, what I claim to be 40 new and desire to protect by Letters Patent is—

1. A crate having side and end sections, a cover for closing the crate and adapted to rest with its ends on opposite of said sections, said cover consisting of longitudinal and transverse slats all of which are rigidly connected and being arranged between the upper ends of the other of said sections, and locking devices slidably arranged on the 45 cover for engagement with said other sections for locking the cover in place, said locking devices being movable only when the cover is depressed at a point intermediate its ends.

50 2. The combination with a crate having hingedly connected side and end sections, of a detachable cover section for closing the crate, said cover section being arranged to rest with its ends on the end sections and to fit between the upper ends of the side sections to brace the crate in a rectangular position and locking members projecting laterally from the sides of the cover for locking engagement with said side sections, said

locking members being slidable on the cover 65 and provided at their inner and outer ends with angular extensions for limiting their sliding movement.

3. A crate having side and end sections, a cover for closing the crate, a locking bolt 70 slidably secured to the cover for locking engagement with one of said sections said bolt having a vertical extension at its outer end to prevent bulging of the said section away from the cover, said extension also 75 serving to prevent retraction of the bolt except when the cover is depressed.

4. In a crate having a detachable cover, of hooks slidably arranged with respect to the cover and engageable with the walls of 80 the crate, said hooks having upward extensions whereby they may be slidably moved into engaging position with said walls when the cover is pressed down below its normal position.

5. The combination with a box, of a cover therefor adapted to be sprung in respect to its normal position of rest on the box and provided with fasteners adapted for inter-locking engagement with the box and 90 arranged to be held interlocked with the box by the spring tension of the cover.

6. The combination with a box, of a cover therefor adapted to be sprung in respect to its normal position of rest on the box and 95 provided with movable fasteners constructed for interlocking engagement with the box and arranged to be held in interlocking engagement therewith by the spring tension of said cover.

7. The combination with a box, of a cover therefor adapted to be sprung in respect to its normal position of rest on the box and provided with sliding fasteners having bent 100 ends insertable through openings in the box and adapted for interlocking engagement with the box.

8. The combination with a box, of a cover therefor adapted to be sprung in respect to its normal position of rest on the box and 105 provided with sliding fasteners having bent ends insertable through openings in the box and adapted for interlocking engagement with the box and arranged to be held interlocked with the box by the spring tension of said cover.

9. The combination with a box, of a cover therefor adapted to be sprung in respect to its normal position of rest on the box and provided with fasteners in the form of flat 110 metal slides having outturned ends permitting said fasteners limited sliding movements, said box having openings through which the outer flanged ends of said slides 115 may be moved when the cover is sprung, and the said fasteners being held in interlocking engagement with the box by the spring tension of said cover.

10. The combination with a box having sides that project slightly above its ends, said sides having fastener passages in the vicinity of its upper edge, of a cover comprising laterally spaced bars and cross slats, said bars being of a length to rest on the upper edges of the ends of the box, and sliding fasteners working through said bars and having bent ends insertable through the fastener passages of the sides of the box and adapted for interlocking engagement therewith.
11. The structure defined in claim 10 in which said fasteners may be engaged through the fastener passages of said box only when the intermediate portions of the bars of said cover are sprung inward.

In testimony whereof I affix my signature.

CORNELL FLAGSTAD.
